JESSE H. ERSTEIN, OF LARCHMONT, NEW YORK

LINING FOR HATS

Application filed November 13, 1929. Serial No. 406,806.

My invention relates to linings for hats, and more particularly to linings for hats for feminine wear, although as will be evident my improved lining material may be used for other purposes.

Heretofore, in preparing the material for hat linings, it was customary to use a light material such as silk taffeta, the material being cut on a bias to the desired width and length, both lengthwise edges hemmed, and then the ends were sewed together. If a band effect, such as a sweat-band, was desired, it was necessary to sew such taffeta lining to a heavier material or ribbon. In some instances such linings were sewed to a crown piece, and where no crown piece was employed, the inner edge of the lining was either sewed to the hat crown, or a draw-string was drawn through the hem at the inner edge of the lining for drawing the lining into a shirring, and finally it was necessary to sew the outer edge of the lining to the hat at or near the rim. Such linings required considerable sewing to fit and adapt them to a hat, and at best it was not always a neat appearing and well finished piece of work owing to the number of seams and class of material employed.

The object of my invention is to overcome these objectionable features and to furnish a single piece lining for hats in which the lining proper and a sweat-band will be woven in one piece, and which will require but one seam where the ends are joined. With such a lining it will also be possible to take advantage of all color and design effects made possible by modern methods of weaving, and thus not only will the amount of work involved in applying linings to hats be reduced to a minimum, but such lining will permit unlimited variations to produce artistic effects. A very important feature of my invention is the weaving of a sweat-band integral with the lining, and preferably, making the sweat-band part of the lining of a heavier weave than the other part. This not only reduces the amount of work involved in applying linings to hats, but also results in a more finished appearance, and is especially useful, due to the weave of the sweat-band,

for preventing the hat size stretching in wear.

In carrying my invention into effect, I provide a specially woven fabric having in the preferred form a band section of a relatively heavy weave, such as belting, grosgrain, satin or twill weaves, to form the sweat-band part of the lining; an intermediate lighter woven section which may be more properly termed the lining as distinguished from the sweat-band section, such intermediate section being of a taffeta weave, although a light satin or messaline weave may be used; and at the other edge a double or tubular weaving, or tubular selvedge, is provided through which a draw-string or narrow ribbon may be drawn, or if desired, the tubular weave may be formed on the draw-string. It will be evident from the foregoing description of my improved form of lining that the weaving will be done in the manner of weaving ribbon; and that various color and design effects may be produced to effect pleasing and harmonious combinations with the color and hat design. In the use of my lining ribbon all that is necessary in the way of preparation is to cut off the desired length for a hat lining from a roll of my special lining ribbon, either with a straight or slightly diagonal cut according to the shape of the hat, and then sew the ends together, leaving the tubular edging free for the draw-string. If the tubular edge is woven without the draw-string, the cord, ribbon or tape used for this purpose may be inserted with the usual bodkin needle either before or after the ends of the lining are sewed together. No other sewing is necessary except the usual stitching of the lining to the rim of the hat. After that is done the draw-string is adjusted to impart the desired shirring to the lining.

My invention is illustrated in the accompanying drawings in which, Figure 1 is an inverted view of a hat for feminine wear showing the application of my improved lining in its simplest form; Figure 2 a plan view of the ribbon lining embodying my invention and illustrating a plain two or three color effect, as well as the heavy sweat-band.

and tubular weaves, with a draw-string drawn into the tubular weave.

Referring to Figure 1 of the drawings, 1 indicates a hat which may be of any type 5 for feminine or masculine wear, and 2 indicates my improved lining ribbon. This ribbon as shown, is woven with three distinct parts or sections. As illustrated in Figure 2, part 3 of the ribbon is of a relatively 10 heavy weave intended to serve as the hat band, or sweat-band. The intermediate part 4 is of a lighter weave and serves as the hat lining proper. Part 5 may be of a somewhat heavier weave than part 4, or the 15 same as part 3, and is woven in tubular form. It will be understood that this lining and sweat-band combination will be woven in a single weaving operation as will be readily understood, but since this operation forms 20 no part of the present invention the method of producing the ribbon need not be described. While I have shown the ribbon as woven in three longitudinal parts differing in weight or thickness and color, it will be 25 understood that the weight, color combinations, or design effects of the several parts may be varied at will without departing from the spirit of my invention, the intermediate part 4 especially being adapted to 30 various color and design effects. When the ribbon lining is cut to lengths suitable for hat linings, a draw-string, tape or ribbon 6 is drawn through the tubular part 5. After 35 the ends of a piece of ribbon lining are sewed together, it is placed within a hat as shown in Figure 1, the edge of sweat-band 3 is stitched to the hat along the line 7, Figure 1, and then draw-string 6 is caused to gather the lining part 4 to the desired extent and 40 the ends of the draw-string are secured in any desired manner, as for instance in a bow-knot as shown in Figure 1.

What I claim is:

1. As a new article of manufacture, a hat 45 lining ribbon woven in a single width of three different weaves extending lengthwise of the ribbon, one part extending along one edge being of heavy weave, an intermediate part of lighter weave, and a third part woven 50 in tubular form extending along the other edge of the ribbon.
2. As a new article of manufacture, a hat 55 lining ribbon woven in a single width of three different weaves extending lengthwise of the ribbon, one part extending along one edge being of heavy weave and constituting the sweat-band part of the lining, an intermediate part of light weave for the crown lining, and a third part woven in tubular form ex- 60 tending along the other edge of the ribbon and arranged to contain a draw-string.

This specification signed at New York city, in the county and State of New York, this 4th day of November, 1929.

65 JESSE H. ERSTEIN.
